UNITED STATES PATENT OFFICE.

JOHN STOCKFLETH, OF NEVADA CITY, CALIFORNIA.

BREAST-BOARD FOR UNDERGROUND MINING.

No. 835,839.

Specification of Letters Patent.

Patented Nov. 13, 1906.

Application filed March 22, 1906. Serial No. 307,469.

To all whom it may concern:

Be it known that I, JOHN STOCKFLETH, a citizen of the United States, residing at Nevada City, in the county of Nevada and 5 State of California, have invented new and useful Improvements in Breast-Boards for Underground Mining, of which the following is a specification.

My invention relates to what I call a 10 "breast-board" or apparatus to retain soft ground in mining and like operations and prevent its flowing or falling into the excavation, so that the lagging may be placed and the breast of the excavation advanced.

15 It consists in the combination of parts and in details of construction, which will be more fully explained by reference to the accompanying drawings, in which—

20 Figure 1 is a longitudinal section of my breast-board. Fig. 2 is a view from the inside. Fig. 3 is a transverse section through *v v*, Fig. 1. Fig. 4 is a view similar to Fig. 2, showing two bars 8 and gates 10. Fig. 5 is a view showing the application of my invention.

25 In working mining and other ground where excavations are to be made, and especially where the ground is soft or inclined to slide or cave, it is necessary to timber up the excavation as fast as it is completed. This is effected by sets of timbers composed of two posts, a cap, and a mudsill, with bridging-strips supported by bridge-blocks to make room for the lagging to slip in. This lagging consists of

30 heavy planks 3, which are driven in behind the timbers and are guided by the bridge-pieces and by what are called "false sets," as at 3^a, these being temporarily put in place, so that the lagging can be driven forward and 35 guided in the operation. The top and sides are thus protected as fast as the excavation goes on. In order to protect the front or 40 breast of the excavation and prevent the earth from caving or moving into the excavation, breast-boards are employed. It is 45 the object of my invention to so dispose of these breast-boards that they can be easily set and removed as the excavation advances.

4 and 5 are sections of breast-boards which 50 are made in two parts and are hinged together, as at 6. The ends of these boards are beveled and may be shod or otherwise formed, so that they can be introduced behind the vertical timbers, projecting far enough in 55 each direction so that they are supported by the timbers. By reason of the hinges

these breast-boards can be easily inserted by folding them to such an extent that one or both ends can be passed across the lagging, and the boards are afterward brought into a 60 substantially straight line and then locked in position. Thus each board being placed, a wall will be formed from the bottom to the top which holds the material of the breast in place. Then by removing the boards one at 65 a time the material may be excavated and the breast-board advanced until another set of timbers and lagging may be placed, and the breast is continually advanced in this manner as the work progresses. 70

In order to retain the hinge-pieces in proper alinement after they are straightened out, I employ a heavy bar or bars 8 of sufficient stiffness. One end of the bar or bars is riveted or otherwise secured to one part of 75 the breast-board. The other part of the breast-board may be bent or folded independent of this free end of the bar. When the breast-board has been brought into a straight line, the breast-board will be substantially parallel with this bar, and by means of a slidable link or other form of latch carried by that part of the breast-board which is free from the bar the end of the bar may be engaged with the breast-board, and 80 the bar is thus practically fixed rigidly to both parts of the breast-board, and thus maintains it in its straight position and against any tendency of the earth behind to press it inwardly. 85

As shown in Fig. 3, a single bar is employed, which may be made of angle, T, or other form of iron which will give rigidity.

As shown in Fig. 5, two bars are attached to the breast-board intermediate between the top and bottom, and the free ends are brought together to form a single piece for engagement with the link or latch. 95

Boards made in this manner can thus be introduced, the ends being supported against 100 the front ends of the lagging on each side, and one end is introduced behind one of the lagging-planks far enough to pass the corresponding lagging on the opposite side, after 105 which the board would be moved back, so that both ends rest against the ends of the lagging. The whole front or breast is thus protected. In order to remove the earth or material from behind these boards, it is necessary to remove one board at a time, excavate as far as may be safe or desirable, and then drive the corresponding lagging for 110

ward and replace the breast-board, commencing, preferably, at the top and working downward with each board successively.

In my invention I have shown gates 10, 5 which are hinged and slidable or otherwise removable. These gates may be as many in number as the length of the board and the exigencies of the work require and cover-openings made through the breast-board. 10 The gates are normally latched or secured, as at 11, and when the boards have been set and it is desired to excavate behind them one or more of these gates may be opened at a time and they will each expose a sufficient 15 opening, so that the material may be withdrawn from behind the board without exposing the excavation to the danger of a sudden rush or cave of the material which might occur in very soft ground.

20 The breast-boards may have handles fixed to them at or near the center for convenience in taking down and putting up.

Having thus described my invention, what I claim, and desire to secure by Letters Patent, is—

1. In mining and like appliances, the combination with sets of timbers and suitable guide means, and lagging inserted behind the timbers, of breast-boards having a length sufficient to extend across the lagging at each side of the excavation, the said boards having hinges intermediate of their length whereby they may be folded to pass the supports, and means for locking the sections in a substantially straight line.

2. Breast-boards for mining and like ex-

cavations, said boards made in a plurality of parts and hinged together whereby they may be folded so that the ends can be introduced behind supporting-timbers, and the board returned to a substantially straight line, means for locking the boards in such line, said means consisting of bars riveted to one section of the board, and having the free end extending beyond the hinge and over the other section, and means for securing said free end to the opposite section of the board, said boards having means permitting the removal of material without altering the position of the boards.

3. Breast-boards for mining and like excavations having a length sufficient to extend across the excavation, supporting-lagging across which the ends of the boards are extended, hinges intermediate of the ends of the boards whereby the board may be folded so that its ends will pass the supports, rigid bars fixed to one section of the board and latches by which the opposite ends may be fixed to the free ends of the boards, when the two boards are in alinement, and gates and door-openings made through the boards whereby material may be removed without disturbing the boards.

In testimony whereof I have hereunto set my hand in presence of two subscribing witnesses.

JOHN STOCKFLETH.
